UNITED STATES PATENT OFFICE.

GERALD S. CARRICK, OF CHICAGO, ILLINOIS, ASSIGNOR TO CARL SCHOLZ, TRUSTEE, OF CHICAGO, ILLINOIS.

GRATE-BAR.

1,218,594.

Specification of Letters Patent.

Patented Mar. 6, 1917.

Application filed July 6, 1915. Serial No. 38,255.

To all whom it may concern:

Be it known that I, GERALD S. CARRICK, a citizen of the United States, residing at Chicago, in the county of Cook and State 5 of Illinois, have invented a certain new and useful Improvement in Grate-Bars, of which the following is a specification.

My invention relates to that class of grates in which a forced draft is used, and 10 is designed as an improvement on grates of this class while utilizing the principal features thereof, and is designed to avoid the use of the filler which is sometimes employed intermediate the grate bars. This 15 filler has two objectionable features, primarily that it is very expensive to put in, another that if the grate bars expand, owing to the heat, they are liable to bulge the side walls of the furnace.

20 My invention has for its object to provide an improved form of grate bar which will avoid the necessity of using the filler, and which will permit the bars to expand without doing any damage to the inclosing 25 structure, and while primarily intended to present a tight surface, are so arranged that should they become slightly separated, the shape of the bars would be such as 30 would serve to avoid any deleterious result.

My means of accomplishing the foregoing objects may be more readily understood by having reference to the accompanying drawings which are hereunto annexed and 35 are a part of this specification, in which:

Figure 1 is a fragmentary view of the top of two of my grate bars.

Fig. 2 is a side elevation of the same.

Fig. 3 is a cross section taken on the line 40 $x-x$ in Fig. 1.

Similar reference numerals refer to similar parts throughout the entire description.

As shown in the drawings, the grate bars are provided with top walls 1, and side 45 walls 2 and 3, the lower portion of which tapers inwardly and terminates in a longitudinal flange 4. In my bar the vertical portion of the side wall 2, adjacent the top wall 1 is beveled as at 5, while the corresponding portion of the side wall 3, is provided with an angular outwardly extended portion 6, the angle of the lower surface 7, of the angular portion 6, being preferably of lesser degree than the angle of the beveled surface 5.

When the bars are placed in position, an opening is left between them, which is closed at the top by the point of the angular portion 6, engaging the top of the beveled portion 5. This makes a tight joint, 60 and serves to prevent any undue escape of air. However, should the bars become separated and the air escape through the opening intermediate the two walls 2 and 3, it will be apparent to persons skilled in the art that this separation will have no deleterious effect upon the fire, inasmuch as the inclined walls will serve to direct the air in an oblique line of travel through the fire, thereby attaining a somewhat similar 70 effect to that produced by the shape of the arcuate slots in the top of the wall 1, shown in the drawings.

The result of this construction is as follows:

When the bars are installed in the furnace, they are fitted in so that the point of the angularly extended portion 6, contacts with the point of union of the beveled portion 5, with the surface of the top wall 1, 80 there being a space intermediate the two inclined surfaces and the vertical portion of the walls 2 and 3.

It will be apparent from the foregoing description that when the fire is kindled 85 in the fire box and the bars expand due to the heat, that the point of the angularly extended portion will slip past the point of union of the beveled portion 5, with the surface of the top wall 1, as indicated by 90 the dotted lines, without doing the slightest damage to the retaining walls of the furnace. At the same time, it will be apparent that the necessity for the filler between the walls 2 and 3, is entirely obviated and all 95 the trouble and expense connected with this installation is done away with without sacrificing any of the efficiency of the furnace. This also provides a larger cooling surface which lengthens the life of the grate bar, 100 as it keeps them much cooler than can be done when the filler is employed.

Having described my invention what I regard as new, and desire to secure by Letters Patent is:

1. In a forced draft furnace, a plurality of hollow grate bars, having top, end and side walls, the upper portion of one of the side walls, adjacent the top wall, being beveled, a corresponding portion of the 110

other wall being provided with an angular outwardly extending portion of lesser degree than the angle of the beveled portion on the adjacent grate bar.

- 5 2. A hollow grate bar for forced draft furnaces, with top, end and side walls, one of said side walls being beveled adjacent the top wall, the other having an outwardly extended portion, the lower surface of
10 which is inclined.

3. A hollow grate bar for forced draft furnaces, with top, end and side walls, one side wall having an inclined portion adjacent the top wall, the other side wall having an outwardly extended portion, having ¹⁵ an inclined lower surface of a different angle than the beveled portion.

In testimony whereof, I have signed the foregoing specification.

GERALD S. CARRICK.
